UNITED STATES PATENT OFFICE

2,532,521

ROLLING BALL AND TRACK TOY

Ray L. Stair, San Fernando, Calif.

Application November 13, 1946, Serial No. 709,488

3 Claims. (Cl. 46—43)

1

My invention relates generally to toys, more particularly to a toy comprising a track and a ball adapted to roll thereover, as a result of momentum gained by said ball as it travels down an inclined portion of the track and the principal objects of my invention are, to provide a toy having a track formed of flexible material in order that it may be laid in various positions on the floor or ground, to form the track in sections, with means for readily connecting and disconnecting same, to provide an adjustable vertical support for one end of the track and further, to provide simple means for slightly elevating the track at any desired point throughout its length and particularly on curved portions thereof.

With the foregoing and other objects in view my invention consists in certain novel features of construction and arrangement of parts which will be hereinafter more fully described and claimed and illustrated in the accompanying drawings, in which:

Fig. 1 is a side elevational view of my improved toy with parts thereof in section.

Fig. 2 is a vertical section taken through the upper portion of the standard that supports one end of the track.

Fig. 3 is a horizontal section taken on the line 3—3 of Fig. 1.

Fig. 4 is an enlarged horizontal section taken on the line 4—4 of Fig. 1.

Fig. 5 is an enlarged cross section taken on the line 5—5 of Fig. 1.

Fig. 6 is an enlarged cross section taken on the line 6—6 of Fig. 1.

Fig. 7 is an enlarged cross section taken on the line 7—7 of Fig. 1.

Referring by numerals to the accompanying drawing which illustrates a preferred embodiment of my invention, 10 designates a disc like base provided in its top with a shallow recess 11 and rising from the center of said base is a tube 12. Arranged for telescopic movement in the upper portion of tube 12 is a smaller tube 13, carrying an adjustable friction collar 14 of rubber that is adapted to rest on top of tube 12 and thus hold tube 13 in differently adjusted vertical positions.

Arranged for sliding movement in the upper portion of tube 13 is a rod 15 carrying an adjustable friction collar 16 of rubber adapted to rest on top of tube 13.

The upper portion of rod 15 is bent downward to form an angularly disposed finger 15a which enters and supports the elevated end of the track (see Fig. 2).

The parts 12, 13, 14 and 15 provide a vertically adjustable post or standard for the inclined end portion of the track.

The track or single rail which is formed in sections of any desired length, is composed of rubber or rubber composition, that is extruded so as to form a base 17 having a flat under face 18 and a pair of upwardly projecting diverging flanges 19 that provide a groove 20, transversed by the rolling member 21, preferably a ball such as is used in conventional ball bearings.

As shown in Figs. 6 and 7, the side faces of rail base 17 incline inwardly from under face 18 toward the lower portions of flanges 19 and thus the lower portion of said rail base is substantially fish-tail shape in cross section.

Formed in base 17 is a continuous bore 22, thus enabling the ends of the track sections to be detachably connected by means of inserted pins or wire rods such as 23.

The upper portion of the bore in the track section A that is held in inclined position by the adjustable standard, receives the finger 15a at the upper end of rod 15 (see Fig. 2), and the intermediate portion of said bore is occupied by a fairly stiff wire 17a, (see Fig. 1) which holds section A rigid and straight.

The track may include a circular loop section B held in shape by a wire 24 inserted in the bore in said section, one end of which wire is extended beyond the end of said section, for insertion in the lower end of the bore in inclined section A.

The track also includes one or more sections such as C and D of various lengths, the ends of which are detachably connected by means of inserted pins or wire rods such as 23. The track or rail being flexible, may be laid in any shape or course on the floor or ground, over small blocks or the like in simulation of overpasses (see Figs. 1 and 5), and the end of the track opposite the inclined end, may terminate above base 10, so that the balls discharge into recess 11 from which they may be readily transferred to the upper end of inclined track section A.

In Fig. 5, I have shown a semicircular block 25 of rubber or the like provided in its upper face with a plurality of dovetail notches 26 adapted to receive the fish-tail shaped base portion of the track rail, such block being used for the support of the rail where same is laid on a short curve.

On a straight track, the rail is seated in the central or uppermost notch 26 and on curves, the rail is seated in either one of the lower or lateral notches, thus positioning the flanges 19 and

groove 20 of the curved portion of said rail, so that the rolling balls will not leave the track as a result of centrifugal force.

In playing with the toy the balls are placed on the upper end of track section A and after rolling down same said balls traverse the loop B and then roll at reduced speed along the track sections C and D.

In addition to providing an interesting and entertaining toy and plaything my improved toy has definite educational functions and value, inasmuch as it can be used for teaching the fundamentals of road building, speed and acceleration of the rolling balls on straight and curved portions of the track, also the influence of centrifugal forces on the balls as they traverse the track's curves.

Minor changes in the size, form and construction of the various parts of my improved rolling ball and track toy may be made and substituted for those herein shown and described without departing from the spirit of my invention, the scope of which is set forth in the appended claims.

I claim as my invention:

1. In a rolling ball and track toy, a base provided in its top with a shallow recess, a tubular standard projecting upwardly from said base, a tubular member mounted for vertical adjustment in said tubular standard, a stop adjustably mounted on said tubular member, a rod mounted for vertical adjustment in the upper portion of said tubular member, a stop adjustably mounted on said rod, an inclined arm projecting from the upper end of said rod, a track rail having one end supported by said inclined arm, and comprising a plurality of sections of flexible material, each provided in its top with a longitudinally disposed groove and in its body with a continuous bore, pins removably seated in the ends of the bores in adjacent rail sections for connecting same and

inflexible rods inserted in the bores of certain of said rail sections to render same rigid.

2. The rolling ball and track toy as set forth in claim 1, with a track supporting block provided with an arched upper face in which are formed spaced undercut transverse notches for reception of the lower portions of the track rail sections and a rail section seated in one of said transverse notches.

- 10 3. In a rolling ball and track toy, the combination with a track rail provided in its top with a continuous groove, one end of which track rail is inclined, of a support for the inclined end of said track rail, which support comprises a base provided in its upper surface with a recess for reception of the balls used in play with the toy, a tubular standard projecting upwardly from said base, a tubular member telescoping into said standard, a stop adjustably mounted on said tubular member above said standard, a rod telescoping into the upper portion of said tubular member, a stop adjustably mounted on said rod and an inclined arm projecting from the upper end of said rod and removably seated in the upper end of the inclined portion of said track rail.
